UNITED STATES PATENT OFFICE.

EZRA W. CARTER AND DAVID R. SMITH, OF COHOES, NEW YORK.

FILTERING-PAPER.

SPECIFICATION forming part of Letters Patent No. 313,174, dated March 3, 1885.

Application filed September 18, 1884. (No specimens.)

To all whom it may concern:

Be it known that we, EZRA W. CARTER and DAVID R. SMITH, both of Cohoes, county of Albany and State of New York, have invented a new and useful Improvement in Filtering Paper, of which the following is a full, clear, and exact description, reference being had to the accompanying drawings, making part of this specification.

10 Our invention relates to strengthening the central portion of sheets of filtering-paper. The sheets of the filtering-paper of commerce being of uniform thickness throughout, are when in use liable to tear or burst at or near the center because of their then saturated condition, and because the pressure of the contained liquid is greatest at its greatest depth, which is at or near the center of the folded containing-sheet.

15 Our invention consists of a sheet of filtering-paper made thicker at and near its center than toward its circumference.

In the accompanying drawings, Figure 1 represents a face view of a sheet of filtering-paper having our improvement, and Fig. 2 represents a magnified sectional view through the center of Fig. 1.

20 *a* is the central portion, which in our invention is of greater thickness than is the part *b* nearer the circumference of the sheet. The additional thickness required near its central portion may be given to the paper during the process of manufacture by applying a patch

to that central portion, the pulp for the sheet and that for the patch being run into separate sieves or molds of the desired form and size, and the patch applied to the central portion of the sheet while both are in a semi-solidified condition, subsequent pressure between sheets of felt expressing the water and causing the patch and sheet to adhere together, forming one body.

Instead of using the two sieves, we accomplish the desired result with one sieve or mold only by making the sieve or mold deeper at 35 and near the center than near the circumference in order to receive, hold, and deposit more pulp to form the central than to form the outer portion of the sheet. We do not confine ourselves, however, to the means or 40 methods employed in the process of manufacture; but,

Having now described our invention, what we claim as new, and desire to secure by Letters Patent, is—

25 As an article of manufacture, a sheet of filtering-paper thicker at and near its center than near its circumference, substantially as described.

In testimony whereof we have hereunto set 50 our hands.

EZRA W. CARTER.
DAVID R. SMITH.
